In Belgium November 9, 1933

12 Claims. (Cl. 123—119)

The invention relates to carburetors, particularly for internal combustion engines, and especially to carburetors which are provided with auxiliary carbureting means for use when the engine is cold.

The invention relies on the temperature of the engine or some part thereof to control the auxiliary carbureting means. The primary object of the invention is to provide a device of this type, controlled by a thermally sensitive element, in which the thermal element alone is not relied on to control the auxiliary means directly, but such thermal element controls a pressure operated means which in turn controls the auxiliary means.

The second object of my invention is to provide an arrangement of this type in which the pressure used for operating the auxiliary control means is derived from the engine, so that the auxiliary means is controlled both by the temperature and by the pressure. More particularly, my invention comprises an arrangement in which a valve controls the auxiliary fuel supply means, this valve being controlled by the pressure or suction in the induction pipe of the engine, the action of which on the valve is in turn controlled by a thermally responsive element.

Still another object of my invention is to provide an arrangement of this type in which not only the passage through which the mixture produced by the auxiliary carbureting means flows, but also the nozzle of such auxiliary means, are both controlled by temperature and pressure.

In order that the invention may be better understood it will now be described with reference to the accompanying drawings, in which:—

Fig. 1 shows diagrammatically and in vertical section a carburetor constructed according to one embodiment of the invention.

Figs. 2, 3, and 4 show variations of the carburetor according to Fig. 1.

Fig. 5 shows a part of the carburetor indicated on Fig. 1 but arranged according to a second embodiment of the invention.

Fig. 6 shows a variation of the arrangement according to Fig. 5.

Fig. 7 shows the same part of the carburetor according to Fig. 1 but arranged according to a third embodiment of the invention.

Fig. 8 shows a variation of the arrangement according to Fig. 7.

Fig. 9 shows the same part of the carburetor according to Fig. 1 but arranged according to a fourth embodiment of the invention.

Fig. 10 shows a variation of the arrangement according to Fig. 9.

Fig. 11 shows, diagrammatically and in vertical section, a carburetor constructed according to a fifth embodiment of the invention.

Figs. 12, 13, and 14 show variations of the arrangement according to Fig. 11 in combination with the arrangement according to Fig. 5.

Fig. 15 shows, in similar section, a carburetor constructed according to a sixth embodiment of the invention.

Fig. 16 shows a variation of Fig. 15 in combination with the arrangement according to Fig. 5.

Fig. 17 shows a variation of Fig. 11 in combination with the arrangement according to Fig. 1.

Fig. 18 shows a variation of Fig. 15 in combination with the arrangement according to Fig. 1.

Figs. 19 and 20 show a variation of Fig. 15 in combination with the arrangement of Fig. 1.

Fig. 21 shows the same variation of Fig. 15 as Figs. 19 and 20 in combination with the arrangement according to Fig. 5.

Fig. 22 shows a variation of Fig. 11 in combination with the arrangement according to Figs. 9 and 10.

Figs. 23 and 24, finally, show variations respectively of the arrangements of Figs. 1 and 5.

The invention will be further described with reference to a carburetor comprising an auxiliary or starting carburetor for effecting the starting and the operation when cold of internal combustion engines, wherein this auxiliary carbureting arrangement embodies control means for bringing it into or out of action and, in some cases, means for controlling its regulating means while in action.

In a general way, the carburetor shown on Fig. 1 comprises, on the one hand, a float chamber 1, jets 2 and 3, a slow running passage 4 (forming the principal carburetor), suction pipe or conduit 5 with its throttling valve 6 and, on the other hand, an auxiliary carburetor for example of the type described in U. S. A. patent specification 1,958,818 and constituted in substance by a suction passage 7, a calibrated feed orifice 8 situated at the base of a well 9 in which dips a spraying passage 10 which feeds at 11 into the mixture chamber 12 with an air intake 13 which chamber is connected to the suction pipe beyond the throttling valve 6 by means of a valve 14 which controls the outlet 15.

As shown in Fig. 1, the valve 14 is solid with a deformable diaphragm 16 separating the chamber 12 from a chamber 17 which is connected on the one hand to the pipe 5 by a calibrated passage 18.

and, on the other hand, to the atmosphere by a larger passage 19. The thermally sensitive device constituted, for example, by a bi-metallic strip 20 secured to the exhaust pipe of the engine 21, is arranged in such a way as to be able to close or open, according to the effect of heating the engine, the orifice by which the passage 19 opens to the atmosphere.

If the dimensions of the various parts referred to above have been suitably chosen, the operation of the carbureting device is as follows:

The engine being stationary and cold, the thermally sensitive device 20 is contracted and occupies a position in which the orifice through which the passage 19 opens to the atmosphere, is closed. When the engine is set into operation, the passage 19 being closed, the suction in the pipe 5 is transmitted entirely to the passage 18 into the chamber 17. At the same time as the same suction transmitted into the mixture chamber of the auxiliary carburetor is moderated by the entry of air to the orifice 13 into the said chamber, the pressure in the chamber 12 is relatively greater than in the chamber 17. It follows that the diaphragm 16 is pressed towards this chamber 17 and that the valve 14 is maintained in a position for which the outlet 15 is open and the auxiliary carburetor is thus in operation. With the heating of the engine, however, the heat transmitted by the exhaust pipe 21 to the device 20 expands the latter in the direction of opening the orifice of the passage 19 to the atmosphere so that the atmospheric pressure acts through the passage 19 in the chamber 17 to modify and substantially replace the suction of the engine transmitted by the passage 18. When the pressure becomes greater in the chamber 17 than in the chamber 12, the diaphragm 16 and the valve 14 are moved in the direction of closing of the outlet 15 and the auxiliary carburetor is isolated from the pipe 5 and put out of action.

On Fig. 2 a second automatic valve 22 is provided which is lifted by the suction of the engine and depressed by a spring 23, and said valve is interposed between the outlet 15 of the mixture chamber 12 and the final outlet 24 leading to the suction pipe. This addition is provided in order to prevent a pressure surge from the engine from producing sudden movements of the diaphragm 16 in the chamber 12 in the case of uncertain or incorrect starting.

Fig. 3 shows a variation of the arrangement according to Fig. 1 wherein the deformable element or diaphragm 16 is replaced by a movable element or piston 16 of which the opposed faces are subjected to the effect of the pressures existing respectively in the chambers 12 and 17.

Fig. 4 shows a variation of the arrangement according to Fig. 1 wherein the passage 18 which establishes in a permanent manner the communication between the suction pipe 5 and the chamber 17, is formed axially in the rod of the valve 14, one extremity of this rod being made solid with the central part of the diaphragm 16 and the other extremity being guided in a housing provided in the wall of the said pipe.

In a modified form of the invention arranged inversely to that described above, and shown in Fig. 5, the thermally sensitive device is arranged in such a way as to leave the orifice of the passage 19 open when the engine is cold and to close it when the engine becomes hot. On the other hand, the valve 14 is arranged in such a way as to open the passage 15 when the diaphragm 16 is forced towards the chamber 12.

The operation is then as follows: When the engine is put into operation, the suction transmitted by the passage 18 into the chamber 17 is substantially without any effect since the said chamber is in connection with the atmosphere by the passage 19 while in the chamber 12 the suction is that provided by the operation of the auxiliary carburetor. The pressure being greater in the chamber 17 than in the chamber 12, the diaphragm 16 is forced towards the chamber 12 and the valve 14 is displaced in the direction of opening of the passage 15 until it abuts against a shoulder 25 which prevents the final outlet 24 from being closed.

The auxiliary carburetor is maintained in action by the passage 15-24. When, with the heating of the engine, the device 20 expands and closes the opening of the passage 19, the suction transmitted by the passage 18 into the chamber 17 becoming that of the pipe 5 and acting with its full effect, becomes greater than that of the chamber 12 which is modified by the air intake 13. It follows that the diaphragm 16 is forced towards the chamber 17 and maintains the valve 14 in the position for which the passage 15 is closed and the auxiliary carburetor out of action.

On Fig. 6, this arrangement is provided with a second valve 22 and spring 23 of which the operation has already been explained with reference to Fig. 2.

According to another construction, shown on Fig. 7, the same elements can be assembled in a different way. The chamber 17 is not used and the atmospheric pressure acts in a permanent way on the outer face of the diaphragm 16 and the passage 19 places the chamber 12 into connection with the atmosphere under the control of the thermally sensitive device 20 arranged in such a way as to close this communication when cold and to open it when hot.

In operation when cold, as the chamber 12 is only connected with the atmosphere by the normal air feed orifice 13, the pressure therein is smaller than the atmospheric pressure acting on the external face of the diaphragm 16 and the latter is pressed towards 12 in the direction of opening of the passage 15 by the valve 14. The carburetor is thus maintained in action but when, with the heating of the engine, the device 20 opens the orifice of the passage 19, the pressure in the chamber 12 tends to become equal to the external atmospheric pressure, the diaphragm 16 is pressed in the direction of closing of the passage 15 by the valve 14 and the auxiliary carburetor is put out of action.

It is obvious that one could, as shown in Fig. 8, adopt the opposite arrangement wherein the thermally sensitive device leaves a passage 13-19 open when the engine is cold and closes the said passage when hot, operating by increasing the suction in the chamber 12 upon the closing of the passage 13-19 to displace the diaphragm 16 and the valve 14 towards the position of closing of the passage 15.

In Fig. 9 there is shown another arrangement according to which there is utilized at a distance and by a suitable passage such as 19, the increase of pressure of a fluid contained in a closed space 26 subjected to the heat of the engine for operating the diaphragm 16 and the valve 14.

To this end the diaphragm 16 is arranged between a chamber 12 and a chamber 17, this latter being connected by the passage 19 to the said space in which the pressure increases as a func-

tion of the temperature of the engine. The pressure displaces the diaphragm 16 and moves the valve 14 into a position for which it closes the passage 15 in such a way as to put the auxiliary carburetor out of action.

One can also, as shown on Fig. 10, cause to act on one of the faces of the diaphragm 16, not the suction existing in the chamber 12 but the atmospheric pressure, and this in a permanent manner.

It may be advantageous to arrange between the diaphragm 16 and space at variable pressure 26, a liquid stopper or "siphon" contained for example in a reservoir 27 (Figs. 9 and 10) acting against the said diaphragm and forming part of the passage 19.

In accordance with the second part of the invention, the above described arrangement can then be utilized for reducing gradually the suction in the auxiliary carburetor and, in consequence, the feed of its jet in course of warming up of the engine can be modified, conforming to the conditions of use of carburetors of this kind in which the richness of the mixture should diminish to the extent that the temperature of operation increases.

Thus, when it is proposed to utilize the effect determined by thermally sensitive means of the differential pressures of the displaceable or deformable element of which the position varies with the said pressures for controlling the position of the regulating members of the auxiliary carburetor during the period of operation of the latter, use is made in a general way of the same arrangements as those described above for controlling the valve of the auxiliary carburetor.

As shown on Fig. 11, the regulating element of the auxiliary carburetor is constituted by a needle 28 closing the outlet of the jet 29, the said needle being solid with the deformable diaphragm 16 separating the chamber 12 of the auxiliary carburetor from the chamber 17 which is connected on the one hand to the induction pipe 5 by a calibrated passage 18 and, on the other hand, to the atmosphere by a larger passage 30, the thermally sensitive device 20 being arranged to close or open, according to the effect of the heat of the engine at 21, the orifice by which the passage 30 opens to the atmosphere. The engine being stationary and cold, the device 20 is contracted and occupies the position for which the orifice to the atmosphere of the passage 30 is closed. When the engine is set into operation, the passage 30 being closed, the suction in the pipe 5 is transmitted entirely through the passage 18 into the chamber 17 while it is modified in the chamber 12 by the access of air 13 of the auxiliary carburetor. The diaphragm 16 is pressed towards the chamber 17, the needle 28 is raised and the feed section of the jet 29 is the maximum. But when with the heating of the engine the device 20 is expanded in the direction of opening of the passage 30 to the atmosphere, the atmospheric pressure acts by the passage 30 in the chamber 17 to modify and progressively replace the suction of the engine transmitted by the passage 18. To the extent that the pressure in the chamber 17 tends to equal and exceed that in the chamber 12, the diaphragm 16 and the needle 28 are pressed in the direction of the closing of the jet 29 and the feed of this latter diminishes, which tends to produce the weakening of the mixture as a function of the heating and the increase of the speed of the engine.

On Figs. 12, 13, and 14 it is shown how the control arrangements of the regulating members of the auxiliary carburetor similar to those of Fig. 11 may be utilized in conjunction with the control arrangement of the valve member shown on Fig. 5.

The arrangement for controlling the valve member is arranged, as already indicated in Fig. 5, the thermally sensitive device being arranged in such a way as to leave the orifice of the passage 19 open to the atmosphere when cold and to close it with the heating of the engine while the closing valve 14 is arranged in such a way as to open the passage 15 when the diaphragm 16 is pressed towards the chamber 12. In operation, the chamber 17 is thus in communication with the atmosphere when cold, the diaphragm 16 is pressed towards 12 then with the expansion by the heating of the thermally sensitive device the passage 19 is closed and as to the suction of the engine transmitted into the chamber 17 by the passage 18 becomes greater than in 12, the diaphragm 16 is moved towards 17 and the valve 14 occupies its position of closing of the passage 15.

According to Figs. 12 and 13, there is added to the valve-operating arrangement thus formed, a device for controlling the feed-regulating needle 28 of the jet 29. The needle 28 is connected with a valve 31 on the external face of which is exerted in a constant manner the atmospheric pressure while, on the inner face is exerted the pressures existing in a chamber 32 which is connected on the one hand to the chamber 12 of the auxiliary carburetor by a small orifice 33 and, on the other hand, to the atmosphere by a larger passage 30 of which the outlet is closed when cold by the contraction of the thermally sensitive device and opened when hot by its expansion. The same device is thus utilized to act in the opposite direction on the orifices of the passages 19 and 30 opening to the atmosphere and determining the effect of variable pressure and in opposite directions on the respective control members 16 and 31.

In operation, at stoppage of the engine, the device 20, being contracted, leaves the outlet of the passage 19 open and the atmospheric pressure moves the obturating member 14 into the position of opening of the passage 15 while at the same time it closes the outlet of the passage 30 so that the internal suction of the auxiliary carburetor in the chamber 12 is exerted in the chamber 32 through the orifice 33. The needle 28 under the pressure of its spring 35, follows the valve 31 and opens the outlet section of the jet 29 and thus the capacity for feed is then at a maximum. But with the heating of the engine the device 20 in expanding opens progressively the access to the atmosphere of the passage 30 and of the chamber 32 and the valve 31 under the pressure of its spring 34, is moved in the direction of closing of the jet 29 by the needle 28 so that the feed is progressively diminished as a function of the action of the thermally sensitive device and of the heating up of the engine until the moment when, finally, the expansion of the device 20 closes the passage 19 and the valve member 14 is operated to put the auxiliary carburetor out of action.

In Figs. 12 and 13 the regulating arrangements for the feed of fuel of the auxiliary carburetor form part of those described in U. S. A. patent specification Ser. No. 698,897 as an improvement of the arrangement described in specification 75

1,958,818. This arrangement consists in feeding the fuel under the head of the float chamber through a calibrated orifice (in Fig. 13 the orifice 8) situated at the base of a well 9 open to the atmosphere from which a jet passage 10—11 sucks, so that the fuel thus fed in substantially constant quantity per unit time mixes with the quantity of air varying with the speed of the engine and entering at 13 into the mixture chamber 12 of the auxiliary carburetor. As disclosed in specification Ser. No. 698,897, the feed of this calibrated orifice 8 may be increased at the extreme temperatures, by the action of a thermally sensitive device connected to a needle, or again, this feed may be supplemented by the opening of a second calibrated orifice.

The direct action of the thermally sensitive device has now been substituted by the movement of the member of which the position is a function of the differential pressures regulated in some cases from the distance by the independent action of the thermally sensitive device. In Fig. 12 the regulation is effected on the calibrated orifice itself, 8 or 29, and on Fig. 13, on the supplementary calibrated orifice 29.

In the said patent specification Ser. No. 698,897 there is also shown another method for regulating the feed of the fuel which consists in varying the height at which the jet tube 10 sucks the fuel from the well 9. This jet tube may be formed of two separable sections which may be superposed in such a way that the lower section becomes an extension of the upper section when it is necessary to suck the fuel from a lower level in the well 9. The feed of the calibrated orifice 8 being a function of the difference of height between the constant level in the float chamber and the point of suction of the tube 10, if the upper section is displaceable in height in such a way as to be superposed or not on the fixed lower section, the fuel can be sucked from two different heights, say H and h and have two different feed capacities.

As shown in Fig. 14, in place of the direct action of the thermally sensitive means contemplated in patent specification Ser. No. 698,897 for regulating the position of the upper section of the tube 10, there is employed the action of the control valve 31. The upper face of the latter is subjected to the constant atmospheric pressure by 13¹, while, on the opposite face is exerted the pressure of the chamber 32 connected on the one hand to the suction pipe by the passage 18¹ and, on the other hand, to the atmosphere by the passage 30 of which the outlet is closed when cold by the device 20.

The operation is similar to that of the arrangements shown in Figs. 12 and 13. When cold, the passage 30 is closed by the contraction of the thermally sensitive device and the suction of the engine by the passage 18¹ operates the valve 31 and the upper section of the tube 10 in the desired direction for superposing this latter on the lower fixed section and the quantity of fuel fed by the orifice 8 under the head, say H , in the well 9 and absorbed by the tube 10 is the maximum. With the expansion of the device 20 and the opening of the passage 30 and of the chamber 32 to the atmosphere, the valve 31 returns under the pressure of its spring 36 to the position for which the upper section of the tube 10 is separated from the lower section and only sucks the quantity of fuel fed under a smaller head, say h .

In the embodiment shown in Figs. 15 and 16,

the element of which the position is a function of the different pressures determined by the thermally sensitive means is always constituted for example by the diaphragm 16 of which the outer face is, as in Figs. 7 and 8, subjected to the constant atmospheric pressure while its inner face is subjected to the pressure in the chamber 32 which is connected, on the one hand, to the induction pipe of the engine by a passage 18 and, on the other hand, to the atmosphere by a passage 30 of which the outlet is closed when cold by the contraction of the thermally sensitive device. According to this embodiment, the diaphragm 16 is, in this case, connected to a needle which closes, not the jet 29 itself, but the intake of the air branch 37 into which the said jet feeds.

In operation when cold, the passage 19 is closed by the thermally sensitive device, the suction of the engine transmitted by the passage 18 into the chamber 32 maintains the diaphragm 16 and the needle 28 in position of closing of the air intake of the branch 37, so that the suction of the auxiliary carburetor is a maximum on the outlet of this branch and on the jet 28 and that the feed of this latter is a maximum. With the heating of the engine, the expansion of the device 20 and the opening to the atmosphere of the passage 30, the result is obtained that the diaphragm 16 and the needle 28 return under the pressure of the spring 36, to the position for which the air intake of the branch 37 is open and as the suction drops in this branch as the air intake section increases, the feed of the jet 29 progressively drops.

Fig. 16 shows how the arrangement according to Fig. 15 for the control of the regulating needle 28 of the air intake in the air branch 37—in which feeds the jet 29—may be arranged in conjunction with the arrangement for controlling the valve member of Fig. 5. The arrangement of the assembly and the operation are similar to these described with regard to Figs. 12 and 13. As the direction of displacement of the needle 28 for the regulation of the air intake should in this case be opposite that of the needle 28 of the said Figs. 12 and 13, the chamber 26, in which the pressure operating the valve 31 is variable, is situated below this valve instead of being provided above the latter.

In the arrangement of Figs. 17 and 18 the control member is always constituted by a valve 31 of which one of the faces is subjected to the suction of the auxiliary carburetor while the other face is subjected to the pressure existing in the chamber 32. This latter is connected on the one hand to the induction pipe by the passage 18¹ and, on the other hand, to the atmosphere by the passage 30 of which the outlet is closed when cold by the contraction of the thermally sensitive device. The simplification obtained by the arrangements according to Figs. 17 and 18 consists in utilizing the same valve 31 for controlling simultaneously and by the same displacement the closing valve 14—15 and the regulating needle 28 which acts (Fig. 17) on the feed of the jet 29 or (Fig. 18) on the air intake of the air branch 37 into which the jet 29 feeds.

On Figs. 19 and 20, the arrangement of the assembly is similar to that of the foregoing Figs. 16 and 17. However, it is shown that the displacement of the control member 31 may act, not on the regulation of the feed of fuel by the jet or on the regulation of the small amount of air passing in the branch into which the jet feeds, but

on the quantities of air passing into the auxiliary carburetor and on the suction speed of this air on the jet.

The control valve 31 actuated by the differential pressures—regulated by thermally sensitive means as already described—is combined with the mixture passage 13 in which is situated the jet 29 which opens into the chamber 12. Along this passage additional air apertures 38—39 are provided which are masked (Fig. 19) for the position of full opening of the valve 31 and come into communication with air passages 40—41 (Fig. 20) to the extent that the displaceable assembly is moved towards the position of closing of the branch. The assembly forms a carburetor with a variable air section of the well known type in which the suction on the jet and the feed thereof do not vary proportionally to the quantities of air so that a decrease in the richness of the mixture as the speed of the engine increases may be obtained. It should be noted, however, that, according to the invention, the displacement of the member regulating the access of the air is operated not merely by the suction of the engine as in the carburetors of this type already known but by the differential pressures regulated by the thermally sensitive means.

The arrangement may be advantageously completed by such a form of the part of the passage 13 surrounding the jet 29, that the air passage section around this jet, increases with the displacement of the movable assembly so that the suction speed of the air on this jet is proportionally decreased.

Fig. 21 shows the regulating arrangement of the auxiliary carburetor of Figs. 19 and 20 arranged to operate independently of the valve for bringing the auxiliary carburetor into or out of action, this valve being in this example similar to that of Fig. 5.

Fig. 22 shows an arrangement wherein the variable pressure acting on one of the faces of the control element or diaphragm 16, is the variable pressure or tension of a fluid contained in the closed space 26 subjected to the heat of the engine and utilized to operate any one of the regulating arrangements of the auxiliary carburetor mentioned above, for example that of Fig. 12, the valve 31 being replaced by a diaphragm 31¹.

Finally, on Figs. 23 and 24, there is shown, as a variation of Figs. 1 and 5, the manner in which—when it is necessary only to exert on the inner face of the control member or diaphragm 16 a part of the suction of the auxiliary carburetor—the chamber 12 can be separated into two compartments 12^a and 12^b by a partition 42 pierced with an orifice of desired section 43, the suction of the auxiliary carburetor exerted through this orifice 43 in the chamber 12^b on the diaphragm 16, being modified by a communication 44 of the said chamber 12^b with the atmosphere.

It is well understood that the arrangements forming the subject of the invention may be applied to any type of auxiliary or starting carburetor whatever its method of construction and more especially to carbureting devices for effecting the starting and the running when cold of internal combustion engines comprising means for restricting the feed of fuel to the auxiliary jet while the auxiliary air is progressively increased with the speed of the engine.

Whatever are the methods of realization adopted, it will be seen that the invention is characterized by the use of means permitting the automatic connection and in some cases the regula-

tion of the carburetors for operation when cold by means of an arrangement actuated by the differential pressures of fluid determined from whatever distance is necessary for the convenient arrangement of a thermally sensitive device regulating them.

The invention is not limited to the precise forms or details of construction described, as these may be varied to suit particular cases.

What I claim is:—

1. The combination with an engine carburetor including an induction pipe, main and auxiliary mixing chambers, main and auxiliary jets to feed said mixing chambers, a carburant supply chamber connected to said jets, a throttle valve in said reduction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot and pressure responsive means submitted to the differential action of pressures exerted on its opposite faces for automatically controlling the position of said valve, one of said faces being subjected to the action of a fluid, the pressure of which is modified by a thermally sensitive element subjected to the influence of the temperature of the engine while the other face of said pressure responsive means is subjected to the suction existing in said induction pipe.

2. The combination with an engine carburetor including an induction pipe, main and auxiliary mixing chambers, main and auxiliary jets to feed said mixing chambers, a carburant supply chamber connected to said jets, a throttle valve in said reduction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot and pressure responsive means submitted to the differential action of pressures exerted on its opposite faces for automatically controlling the position of said valve, one of said faces being subjected to the action of a fluid, the pressure of which is modified by a thermally sensitive element subjected to the influence of the temperature of the engine while the other face of said pressure responsive means is subjected to the atmospheric pressure.

3. The combination with an engine carburetor including an induction pipe, main and auxiliary mixing chambers, main and auxiliary jets to feed said mixing chambers, a carburant supply chamber connected to said jets, a throttle valve in said reduction pipe for controlling the mixtures from said chambers for normal running when the

- associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot and pressure responsive means submitted to the differential action of pressures exerted on its opposite faces for automatically controlling the position of said valve one of said faces being subjected to the action of a fluid, the pressure of which is modified by a thermally sensitive element subjected to the influence of the temperature of the engine while the other face of said pressure responsive means is subjected to the suction existing in said induction pipe and simultaneously to the atmospheric pressure.

4. The combination with an engine carburetor including an induction pipe, main and auxiliary mixing chambers, main and auxiliary jets to feed said mixing chambers, a carburant supply chamber connected to said jets, a throttle valve in said reduction pipe for controlling the mixture from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot and pressure responsive means submitted to the differential action of pressures exerted on its opposite faces for automatically controlling the position of said valve, one of said pressures being produced by a fluid subjected to the heat produced by the engine, so that the pressure of said fluid is a function of the temperature of the engine.

5. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, pressure responsive means for automatically controlling the position of said valve, a chamber containing said pressure responsive means, a passage abutting in said chamber, a thermally sensitive device arranged adjacent of a part of said engine for controlling the opening of said passage.

6. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, pressure responsive means for automatically controlling the position of said valve, a chamber containing said pressure responsive means, a tube abutting in said chamber and having its free extremity arranged at a distance of said chamber and opening in the atmosphere and a thermally sensitive device, arranged adjacent of a part of said engine for controlling the opening of said free extremity.

7. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, pressure responsive means for automatically controlling the position of said valve, a second valve independent of said first valve for opening said passage as long as suction exists in said induction pipe and for closing said passage as soon as the pressure therein exceeds the atmospheric pressure, so that the return flow of air towards said independent mixing chamber is prevented.

8. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, pressure responsive means, acting on said valve, for automatically controlling its position, means connected to said pressure responsive means and cooperating

with said independent jet for regulating the mixture, supplied by said independent mixing chamber, by influencing the feed of said jet in such a way that said mixture becomes weaker as the engine warms up.

9. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, a first pressure responsive means acting on said valve for automatically controlling its position, means cooperating with said independent jet for regulating the mixture, supplied by said independent mixing chamber, and a second pressure responsive means, acting on said regulating means by influencing the feed of said jet in such a way that said mixture becomes weaker as the engine warms up.

10. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, a first pressure responsive means, acting on said valve for automatically controlling its position, a chamber containing said first pressure responsive means, a first passage abutting in said chamber, means cooperating with said independent jet for regulating the mixture supplied by said independent mixing chamber, a second pressure responsive means for acting on said regulating means, a second chamber containing said second pressure responsive means, a second passage abutting in said second

chamber, a thermally sensitive device arranged adjacent of a part of said engine for controlling said first and said second passage so as to open the orifice of one and simultaneously to close the orifice of the other of said passages.

11. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, supplementary means by which, at low temperature of the engine and for which the normal regulation of said independent jet is insufficient, an increase of richness of the mixture is obtained, and pressure responsive means for automatically controlling the position of said valve and the bringing into action of said supplementary means.

12. The combination with an engine carburetor including an induction pipe, main and auxiliary mixing chambers, main and auxiliary jets to feed said mixing chambers, a carburant supply chamber connected to said jets, a throttle valve in said induction pipe for controlling the mixtures from said chambers for normal running when the associated engine is hot, an independent mixing chamber for supplying mixture to the engine while cold and opening in said induction pipe at a point downstreamwards of said throttle valve so that the delivery of said independent chamber is not obstructed when said throttle valve is in closed position, an independent jet for supplying carburant to said independent chamber, a passage between said independent mixing chamber and said induction pipe, a valve for stopping the flow of mixture through said passage when the engine is hot, pressure responsive means, acting on said valve, for automatically controlling its position, means connected to said pressure responsive means and cooperating with said independent jet for regulating the entry of a supplementary air inlet to the passage in which said independent jet feeds, by closing said air inlet when the engine is cold and by opening progressively said inlet as the engine warms up, so as to diminish progressively the suction on said independent jet and the quantity of fuel delivered.

MARCEL LOUIS MENNESSON.
